UNITED STATES PATENT OFFICE.

WILLIAM C. LAUTNER, OF ROCHESTER, NEW YORK, ASSIGNOR TO THE IDEAL COUCH AND CASKET COMPANY, OF SAME PLACE.

DESIGN FOR A BURIAL-CASKET.

SPECIFICATION forming part of Design No. 28,675, dated May 17, 1898.

Application filed February 27, 1897. Serial No. 625,423. Term of patent 14 years.

To all whom it may concern:

Be it known that I, WILLIAM C. LAUTNER, a citizen of the United States, residing at Rochester, county of Monroe, State of New York, have invented and produced a new and original Design for a Burial-Casket, of which the following is a full, clear, and exact description, reference being had to the accompanying drawings, which form a part of this specification.

In the drawings, Figure 1 is a view in perspective of the body of a burial-casket, illustrating my design. Fig. 2 is an end view.

The leading feature of my design consists in the form of the body portion.

In the drawings, A represents the body portions of the casket.

A^2 represents the end portions of the body; a^2 , the front portion of the base; a^3 , the back of the body portion, and A^3 the bottom or bed of the body portion, the front, back, and bed being shown in Fig. 1 upholstered.

A^4 is a cove-molding attached to the upper edge of the back a^3 of the body portion. The back a^3 is raised substantially to the height of the casket, while the front a^2 is lowered.

The ends A^2 of the body of the casket descend forwardly from the ends of the cove-molding A^4 upon the back a^3 to the upper edge of the front a^2 of the base.

More particularly, the leading features of my design consist in the form or contour of the ends A^2 of the body portion A, surmounted by the cove-molding A^4 upon the raised back a^3 , and the lowered front portion a^2 of the body 35 intermediate the ends. By forming the ends A^2 of such a contour the bed A^3 of the casket is open to the front, giving to the body of the casket the general appearance of a sofa. The general contour of the upper edges of the ends A^2 , as shown, descends from the back to the front of the body.

What I claim as my invention is—

The design for a burial-casket, as herein shown and described.

In testimony whereof I sign this specification in the presence of two witnesses.

WILLIAM C. LAUTNER.
